G. W. RUBUSH,

MACHINE FOR WASHING DISHES, CUPS, AND CUTLERY.

APPLICATION FILED SEPT. 3, 1913.

Patented July 21, 1914.

1,104,388.

UNITED STATES PATENT OFFICE.

GEORGE W. RUBUSH, OF WASHINGTON, DISTRICT OF COLUMBIA.

MACHINE FOR WASHING DISHES, CUPS, AND CUTLERY.

1,104,388.

Specification of Letters Patent. Patented July 21, 1914.

Application filed September 3, 1913. Serial No. 788,020.

To all whom it may concern:

Be it known that I, GEORGE W. RUBUSH, a citizen of the United States, residing at Washington, in the District of Columbia, have invented a new and useful Improvement in Machines for Washing Dishes, Cups, and Cutlery, of which the following is a specification, reference being had to the accompanying drawings, making a part of this specification, in which—

Figure 1 is a plan or top view of my device showing the double tanks or compartments. Fig. 2 is a central longitudinal section. Fig. 3 is a section on line 3—3, Fig. 1, receptacle C. Fig. 4 is a section on line 4—4, Fig. 1, brackets in tank A. Fig. 5 is a detail section showing a plate being washed. Fig. 6 is a detail section showing the process of drying the plates. Fig. 7 is a detail perspective of the washing and drying mechanism. Fig. 8 is a sectional detail of the side rack or receptacle H—H for holding dishes.

Similar letters of reference indicate corresponding parts in the several figures.

My invention has relation to improvements in dish washing machines and it has for its object to improve, simplify and cheapen the cost of construction of this class of machines, over the prior state of the art, while at the same time, the washing and drying of the dishes and like articles is expedited, thereby saving labor and time to the operator.

With these and other objects in view, my invention consists in the novel construction and combination of parts as will be herein-after more in detail described, and the asserted novelty particularly pointed out in the specification and claims.

Referring to the drawings, Fig. 1, A and B designate double tanks or compartments for holding hot or cold water. Tank A is located at right angles with tank or compartment B, water being drawn into these tanks from any source of supply such for instance, as the house pipes, and may be drawn from the spigots over the kitchen sink, or they may be filled by pouring water into the tanks or compartments by hand. These tanks or compartments may be formed singly and be secured together by any suitable fastening means.

The letter C in Fig. 1 designates a dish or other article drying receptacle located at the rear end of tank B for the reception of

dishes and other articles to be dried. The small letters $a—a$, $a^1—a^1$ designate brackets for holding dishes at an angle of 35 or 40 degrees, $a—a$ represent the upper short rods 60 and $a^1—a^1$ the lower rods in the brackets Figs. 2 and 4. The brackets are formed of a plurality of diagonally disposed short rods having one end secured to a wooden or metal frame. These brackets if preferred may be 65 taken out and replaced again in the same position on each side of the tank or compartment A. The opposite ends of these rods $a—a$, $a^1—a^1$ Figs. 1 and 2, are free to allow the dishes to be withdrawn from between them through the medium of the sponge carrying arm, e, Figs. 1, 2, 5, 6, and 7. The operator may easily remove the dishes from the brackets to tank B and receptacle C.

In order to lighten and facilitate the movements of the machine, a vertically positioned frame b is provided having its lower ends secured to the frame holding the tank or compartment B, about midway the length of said tank, while the top rod of the vertically positioned frame has mounted thereon a hollow cylinder or roller b¹, the rod forming the axle thereof. The belt or chain e⁷ passes over the roller b¹. The lower ends of this belt consist of light springs e⁸—e⁸ having hooked ends secured to the driving rod E, Figs. 1 and 2 by the eyes e⁹.

D—D¹, designate two inverted V-shaped partitions spanning the walls between the tanks or compartments A, B and C, which separates them one from the other serving the purpose through the medium of the conveyer of passing up the dishes and other articles therein into the tank B or receptacle C.

E designates a driving rod, which is provided at the forward end with a cross arm e, Figs. 1, 2, 5, 6, 7, and is securely fastened 100 to said driving rod. By this combination a variety of movements can be made when supported by the swinging frame and belt.

By a variety of movements the dishes are moved from the brackets $a—a$ $a^1—a^1$ to tank 105 B, washed and rinsed and then conveyed to receptacle C and there sponged and dried. The sponge carrying cross arm and its workings is thus fully described: e designates the axle or shaft securely fastened to the driving rod or conveyer E, e¹ designates a washing sponge fastened to shaft e. The

same in operation in tank B, Fig. 5. e^2 the drying sponge, fastened to the other end of said shaft or axle e , Fig. 1. The same in operation in receptacle C, Fig. 6. e^3 designates a dripping pan to catch all surplus water from washing sponge e^1 while the shaft is vertically adjusted in the drying process receptacle C Fig. 6. The said dripping pan is securely fastened to shaft e . e^4 e^5 constitute the bifurcated guard fingers spaced from each end of the shaft — e — and also spaced from the arm — e^5 —. When operating the device, the edges of said dishes are gripped by the bifurcated fingers and arm e^5 . Said arm passes under the edges and lower rims of said dishes and holds them securely by the notched clamp on upper forward end, e^5 Figs. 1, 2, 5, 6, 7, thereby removing dishes from the brackets 20 to tank B and receptacle C at the will of the operator.

When ready for operation proceed as follows: Place the dishes in the brackets a — a^1 — a^1 , pour hot water over the dishes until 25 the stains are removed, rinse with warm water, remove the dishes from the brackets by means of the driving rod E , and its attachments.

The cleansing process in tank B consists 30 in sponging the dishes by vertically adjusting the sponge carrying arm e in tank B, Figs. 1, 2 and 5 and removing said dishes by means of hooks or engaging teeth e^6 , Figs. 1, 2 and 7, over the V-shaped partition D^1 to receptacle C, a mop or sponge d — d being secured to the incline partition D^1 to dry the under sections of the dishes as shown in Figs. 2 and 6. The faces of the dishes are sponged and dried by sponge e^2 , 35 in receptacle C. The dishes are retained at C^2 C^2 , Figs. 1, 2, 3, while the drying process is in operation. After the drying by a slight movement the dishes will gravitate to either 40 side of the V-shaped receptacle C, having the inclined bottom c^1 c^1 , Figs. 1 and 3.

In the construction of this machine we 45 have two methods for cleansing the dishes, the first method as above explained; the second method is as follows: The operator can grasp and remove dishes from the brackets 50 a — a a^1 — a^1 to tank B and hold said dishes

and turn them so that the front and back can be washed with the sponge e^1 and sponged dry with sponge e^2 . After cleansing remove said dishes to receptacle C or H. 55 The dryer or rack H—H extends parallel with tank B, on either side and is securely attached and supported with oblique brace rods h^1 h^1 and parallel rods H^1 H^1 which extends longitudinally, and at the lower 60 edge of said rack or receptacle. The curved base or trough h — h retains the lower edges of said dishes at an angle during the drying process, thereby forming a convenient and useful dryer or receptacle for dishes, during 65 and after the drying process.

Fig. 8 shows the dish in the rack or receptacle H—H. The figure also shows a perspective view of the oblique brace rods h^1 — h^1 . The curved base or trough, with 70 the lower edge of said dishes retained at an incline h — h , thereby completing the dish washing, rinsing and drying process. Also the cleansing process of cutlery, cups, etc. All hereinbefore described and shown in the 75 drawings and specifications. All combined, arranged and operated substantially as and for the purposes herein set forth and fully described.

I hereby reserve the right to make any 80 changes desired within the scope of my invention.

What I claim as new and desire to secure by Letters Patent is—

The combination with a tank, of a supporting frame, a roller journaled upon said frame, a driving rod, a resilient belt over said roller and secured at its free ends to said rod, a cross arm secured at a point adjacent to the end of said rod, forked means 85 carried by said arm and coöperating with the end of said rod for conveying dishes, sponges carried by the opposite ends of said arm, and a pan centrally fixed to said arm, with its open side adjacent to one of said 90 sponges.

In testimony whereof, I affix my signature, in presence of two witnesses.

GEORGE W. RUBUSH.
